UNITED STATES PATENT OFFICE.

WILLIAM S. TROWBRIDGE, OF CHICAGO, ILLINOIS, ASSIGNEE TO AMERICAN STEEL
FOUNDRIES, OF NEW YORK, N. Y., A CORPORATION OF NEW JERSEY.

STRIKING-BLOCK.

1,165,729.

Specification of Letters Patent.

Patented Dec. 28, 1915.

Application filed August 11, 1915. Serial No. 44,893.

To all whom it may concern.

Be it known that I, WILLIAM S. TROWBRIDGE, a citizen of the United States, residing at Chicago, in the county of Cook 5 and State of Illinois, have invented certain new and useful Improvements in Striking-Blocks, of which the following is a specification.

My invention refers to railway cars and particularly to a novel form of striking block for attachment to the end sills of such cars.

It is common practice to provide dead-wood or a striking block on the end sills of 15 cars in order to absorb excessive buffing shocks, this block being located to lie behind a portion of the car coupler. Blocks of cast material are commonly employed but it is well known that castings are sub-
ject to breakage under shocks more quickly than rolled or wrought metal. I have, therefore, designed a striking block adapted to be formed from rolled or forged metal and so constructed as to provide the maximum 25 resistance to distortion. Such a device may be cheaply constructed from plates readily available on the market and is adapted for application to cars having either wood or metal end sills.

Other objects will be apparent from the drawings wherein—

Figure 1 is a top view of the preferred embodiment of my invention; Fig. 2 is a side elevation; and Fig. 3 is a sectional view 35 on line 3—3 of Fig. 2.

Referring to the drawings, 10 is the up-standing leg of the angle attaching portion, and 11 the bottom leg. The block is attached to the end sills of cars in the position 40 shown in Fig. 2, the portion 10 being provided with bolt holes 12, and the bottom 11 with bolt holes 13 through which bolts (not shown) secure the block to the sills (not shown).

In shearing and shaping the plate I provide a centrally disposed tongue which I 45 bend into the shape shown in Fig. 3. The tongue has an upright face 14, a rearwardly inclined top 15 and a vertical end flange 16 which is riveted or otherwise secured

to the leg 10. To increase the strength and rigidity of the stop I prefer to form corrugations or ribs 17 in the top 15 thereby providing a stop of great strength though much lighter than a cast block of 55 the same resistance. The face 14 receives the blows from the coupler head and therefore must be strongly reinforced. To form an abutment for the flange 16 I prefer to turn down a lip 18 in leg 10. This lip will 60 prevent any vertical movement of the flange 16 when blows are struck on the face 14 thereby preventing shearing of the rivets 19 if such are used.

It is obvious that some modifications may 65 be made and such modifications as come within the scope of my claims I consider as within the spirit of my invention.

I claim:

1. In a striking block, the combination 70 with integral vertical and horizontal attaching plates, of a tongue member integral with said horizontal plate, said tongue being bent upwardly and rearwardly and provided with a flanged end; said rearwardly 75 extending portion being provided with ribs, said flange lying against said vertical portion, and fastening means to secure said portions together, substantially as described.

2. In a striking block, the combination 80 with integral vertically and horizontally disposed attaching plates, of a stop member integral with said horizontally disposed plate, said stop member bent upwardly and rearwardly and provided with a flanged 85 end, said rearwardly extending portion provided with ribs, said vertical attaching plate member provided with a forwardly projecting lip, the flanged end of said stop adapted to bear against said vertical plate 90 member and abut against said lip, and means for securing said flanged end to said vertical plate member, substantially as described.

Signed at Chicago, Illinois, this 4th day 95 of August, A. D. 1915.

WILLIAM S. TROWBRIDGE.
